UNITED STATES PATENT OFFICE.

JESSE R. WATKINS, OF ST. JOSEPH, MISSOURI, ASSIGNOR TO THE AMERICAN SOCIETY FOR THE PREVENTION OF CRUELTY TO ANIMALS, OF NEW YORK, N. Y., A CORPORATION OF NEW YORK.

CATTLE-KNOCKING TOOL.

Application filed August 6, 1923. Serial No. 656,092.

The present invention relates to devices adapted for use in cattle slaughtering operations, and aims to provide an improved device of this character which is designed to 5 facilitate those operations and also render the same more accurate and humane.

Accordingly, I have devised an improved cattle-knocking device, adapted to be conveniently wielded by hand, in such a manner as to efficiently puncture and fracture the skull of the animal, with the effect of rendering the animal unconscious preparatory to the use of the knife as the next step of the slaughtering operation. In the use 10 of the improved device, the operator is simply required to lightly tap the head of the animal with the operative point of the tool, which impact sets in operation the essential working mechanism of the tool whereby a punch element is actuated with 15 the required force to puncture and fracture the animal's skull.

In the form of the device which I have devised and found practical, I make use of a 20 cylinder provided with a plunger having a punch element which is actuated for effecting the animal-knocking operation, this plunger being actuated by pressure and its operation adapted to be controlled by the 25 action of a pressure member projecting in position to be engaged with the head of the animal as the operator wields the tool in the knocking operation. The motive medium used for actuating the plunger may be 30 of any desired character, such as gasoline or other forms of explosive media, or compressed air or other simple expansive media, which may be conveniently conducted to the 35 expansion chamber of the tool.

It is also sought to provide a simple, durable and comparatively inexpensive type 40 of construction, whose operation will be extremely efficient, and adapted to displace some of the cumbersome and inaccurate devices now employed.

With the foregoing general objects in view, the invention will now be described with reference to the accompanying drawings illustrating certain forms of construction for embodying the proposed improvement which have been found practical, after 45 which those features deemed to be novel will be particularly set forth and claimed.

In the drawings—

Figure 1 is a side elevation, partially 55 broken away to reveal interior parts, and illustrating a cattle-knocking tool constructed in accordance with the present invention;

Figure 2 is a plan view of the same; 60

Figure 3 is a detail, representing a section taken on the line III—III of Figure 2;

Figure 4 is a view in elevation, similar to Figure 1, but illustrating a different form of construction, adapted for use with compressed air as the motive fluid; 65

Figure 5 is an end elevation of the device shown in Figure 4;

Figure 6 is a detail, representing a section taken on the line VI—VI of Figure 5. 70

Referring now to the drawings in detail, and more particularly to Figures 1, 2 and 3, these illustrate a type of construction embodying the improvements, in which an explosive medium, such as gasoline, is designed to be used as the motive fluid for actuating the plunger which operates the punch element, whereby the knocking operation is effected. In this form of a construction, I employ a cylinder member 8 in which operates a plunger or piston member 9 having connected to its lower face a piston rod 10 preferably of hollow form, as shown, and having the lower end thereof provided with a suitable punch element 11, 85 in the lower or outer end of which is formed a suitable conical recess 12, as illustrated in Figure 1. To the upper end of the cylinder 8 is attached a cylinder head 14 providing a combustion chamber 15 separated from the cylinder 8 by a suitable partition or diaphragm 16 formed with a central passage or port 17, which is intermittently opened and closed by a ground valve boss 18 provided on the upper face of the plunger or 90 piston 9. The port 17 is maintained normally closed by virtue of the plunger 9 being maintained normally elevated in the position shown in Figure 1 by the action of a coil spring 19 the upper end of which is 100 engaged with the under face of the plunger, while the lower end portion of said spring is seated within the fold of a double-walled sleeve 20 attached in projecting relation to the lower end of the cylinder 8; this sleeve 105 20 does not only serve as a seat for the spring 19, but the central passage 21 within said sleeve forms a shield for the punch ele-

ment 11 in its retracted position and also a bearing for the piston rod 10 in the reciprocating movements thereof in response to the action of the plunger 9.

5 The cylinder head 14 is provided with an intake port 22 controlled by an intake valve 23 carried by a sliding valve stem 24 fitted with a spring 25 operating to maintain the valve 23 normally closed but yielding under 10 sufficient pressure to admit a charge of explosive fuel to the chamber 15. The valve port 22 communicates with an intake chamber 26 fitted with suitable conical screens 27 for the purpose of filtering the incoming 15 charge which is conducted to the chamber 26 by way of a passage 28 provided in a valve fitting 29 which is attached to the cylinder head 14. The valve fitting 29 is provided with a valve plug 30 operated by a 20 hand wheel 31 to produce successive half-turns of the valve, the valve plug 30 being provided with corresponding recesses 32 engaged by a suitable catch 33, so that the valve is maintained yieldingly in its successive 25 half-turn positions. In each of these positions the passage 34 of the valve is brought in register with a vent port 35 in the valve fitting 29, and in each half-turn of the valve, the passage 35 is brought in register 30 first with a fuel intake port 36, and second, with an air intake port 37, this port 37 being connected with a pipe 38 leading to any convenient source of air under pressure which may be available. The port 36 is connected with a pipe 39, the other end of which is positioned below the level of the fuel, such as gasoline, within a reservoir 40 which may conveniently be formed as a part 35 of the handle 41 whereby the device is designed to be manually operated, one end of 40 this handle being connected to the side of the cylinder 8, and preferably at right angles thereto. By means of a union 42 and additional handle section 43, the handle may be 45 extended to any desired length. From the air pipe 38, a branch connection 38' is made to the handle member 41, so as to communicate with the interior of the reservoir 40 above the fuel level therein, for the obvious 50 purpose of maintaining the liquid fuel under such a pressure as will cause feeding of the fuel up the pipe 39 into the valve passage 34 whenever the latter is in register with the port 36. Thereafter, when the valve is 55 turned to bring said valve passage 34 into register with the port 37, it is apparent that the air pressure from the pipe 38 will forcibly feed the measured charge of liquid fuel into the intake chamber 26 and likewise force 60 open the valve 23, with the result that the combustion chamber 15 is charged with an explosive mixture of the gasoline, or other liquid fuel vapor, and air. A suitable check valve 7 is preferably fitted in the branch 65 pipe 38', which acts to prevent any of the

liquid fuel from entering the pipe 38 in other positions of the device than that shown.

The cylinder head 14 may be provided with a conventional form of spark plug 45, connected with a lead wire 46 forming a 70 part of a suitable ignition circuit, in which is also included a lead wire 47 having a contact element 48 attached to the cylinder 8, as shown in Figure 1.

The ignition circuit is adapted to be closed 75 through the spark plug by short-circuiting the same through the cylinder and its sleeve extension 20, this operation being carried out by means of a sliding contact element 50 mounted in guide loops or keepers 51 and 80 actuated by a coil spring 52 tending to hold the element 50 in outwardly projecting relation, so that in the welding operation of the implement, in which the opening of the passage 21 is brought against the skull of 85 the animal, the projecting end of the element 50 is engaged and operated against the action of a spring 52, to make contact with the element 48, and thereby close the ignition circuit. This obviously results in the 90 explosion of the charge in the chamber 15, and the consequent downward movement of the plunger in response to the force of said explosion, and the driving of the punch element 11 into the skull of the animal. The 95 movement of the plunger is designed to bring it below a set discharge or exhaust openings 54, permitting the waste gases to escape in this position of the plunger. The stroke of the plunger is of course sufficient to enable it 100 to obtain the required momentum after the explosion to impart the necessary force in the delivery of the punching stroke. In passing below the exhaust openings 54, the plunger's movement is cushioned by the air 105 cushion formed in the space within the lower end of the plunger and inside the sleeve 20, the action of this air cushion also serving to assist or initiate the upward return movement of the plunger, in an obvious manner. 110 The latter part of this return movement is also cushioned by the compression of some air in the upper part of the cylinder 8, such air however leaking past the piston as the plunger settles into the position illustrated 115 in Figure 1.

For convenience as well as compactness of construction, it is preferred to extend the lead wires 46 and 47, as well as the air hose 55, connecting with the pipe 38, through the 120 outer hollow sections 43 of the handle, thus insuring against any of these loose parts interfering with the operation of the device.

It is believed the operation of this form 125 of the construction will be clear from the foregoing, but to summarize the same and assuming that the parts are in the position illustrated in Figure 1, with the plunger 9 maintained in position for closing the port 130

17, the valve wheel 31 is given a half-turn to bring the valve passage 34 into successive register with the ports 36 and 37, which results in the valve passage receiving a measured charge of the fuel from the reservoir 40, and then the feeding of this charge under air pressure from the air pipe 38 into the intake chamber 26. In passing through the screens 27, the fuel mixture is both filtered 5 and broken up into a fine spray and thoroughly intermingled with the air. The air pressure forces the fuel charge past the valve 23 into the combustion chamber 15, the action of the spring 19 being sufficient to maintain the port 17 closed against said air pressure. The device is now ready for the administering of the knocking stroke, in which the operator simply taps the head of the animal at the proper point with the end portion of 10 the sleeve 20, which of course presses the contact element 50 upward and closes the circuit through the engagement of said contact element with the contact 48, thereby exploding the charge in the combustion chamber 15. 15

20 This explosion overcomes the action of the spring 19, and produces a powerful outward movement of the plunger 9 and its punch element 11, the latter being driven into the forehead and brain of the animal. As the 25 exhaust gases escape through the openings 54, the plunger is at once returned to original position by the action of the spring 19, whereupon the subsequent operations are simply a repetition of the one just described. 30

35 The foregoing construction is found to be thoroughly practical for operation in the manner described where the air pressure available for supply to the pipe 38 is as low as 30 to 40 pounds; but where a higher air pressure is available, such as 80 to 90 pounds 40 pressure, the explosive fuel medium may be dispensed with, and air pressure alone used as the motive force for the device, for which purpose I have devised the construction 45 illustrated in Figures 4, 5 and 6 of the drawings. In this form of a device, I use a cylinder 60 in which operates a plunger or piston 61 provided with a piston rod 62 carrying a punch element 63 adapted, by the operation 50 of the plunger, to be projected outward through the guide extension or sleeve 64. The plunger or piston 61 is maintained normally retracted or in its elevated position as 55 shown in Figures 4 and 5, by means of a pair of coil springs 66 attached to the interior of the cylinder head 67, in which position the piston is positively latched by means of a pair of catches 68 slidingly mounted in bearings 69 located at diametrically opposite 60 points on the cylinder 60, as clearly illustrated in Figure 5. These catches 68 are adapted to be actuated by means of pins 70 engaging outwardly inclined slots 71 in vertically movable slides 72 which are connected 65 by rods 73 to the ends of a combined yoke and

pressure member 74 slidably engaging the sleeve 64 and maintained in normally outwardly projecting relation to said sleeve by the action of a coil spring 75 interposed between said pressure member 74 and the lower 70 end of the cylinder 60. Suitable guide lugs or keepers 76 are provided on opposite sides of the cylinder 60 for slidably accommodating the member 72 and rod connections 73. 75

Rotatably mounted in a suitable bearing 77 formed on the cylinder head 67 is a valve plug 78 formed with a right angle valve passage 79 adapted to establish communication between the intake port 80 (leading into the pressure chamber 81 of the cylinder), alternatively, with a vent port 82 and an air intake port 83, the latter being supplied with an air pipe connection 84 leading to any suitable source of compressed air supply; for the sake of convenience, it is preferred to connect the air pipe 84 with the hollow handle 86, which is fitted with a cap 87 having a nipple 88 to which the supply air-hose 89 is connected, as illustrated in Figure 4. 80

85 The valve 78 is manually operated by a hand wheel 90, and the valve is formed with a lug 91 operating between stops 92 approximately 90 degrees apart (see Figure 6), so as to limit the rotation of the valve to a 90 quarter-turn in either direction. 95

100 In the operation of this form of the construction, and assuming that the parts are in the positions shown in Figures 4 and 5, air is admitted to the chamber 81 under the degree of pressure at the source of the supply, and the piston 61 is maintained against movement by its positive engagement with the catches 68. The plunger is therefore 105 in position for operation as soon as the tool is applied in the knocking operation, to present the pressure member 74 to engagement with the animal's head, resulting in upward movement of said pressure member and the outward actuation of the catches 110 68, which obviously results in the release of the plunger 61 to the action of the air pressure, and the driving of the punch element 63 into the forehead of the animal, as in the previously explained operation. 115 In its downward movement, the plunger uncloses the exhaust openings 95, thereby releasing the air pressure above the plunger, whereupon, on the operator's turning the valve to establish communication between 120 the port 80 and the vent port 82 by way of the valve passage 79, the plunger or piston 61 may be readily returned to initial position by the pull of the springs 66, and as soon as the piston has arrived in initial position it is again automatically latched by the springing of the catches 68 (in response to the action of the spring 75) into engagement with the lower margin of the piston. 125 The parts are now in position ready for a 130

repetition of the action just described, on rotation of the valve to original position to renew the pressure in the chamber 81, as will be readily understood.

6 It will therefore be apparent that I have devised a practical and efficient tool or implement adapted for promoting both the speed and accuracy of operations of this character, in that the use of a heavy sledge 10 or the like is dispensed with, and the operator is enabled, by the improved device, to simply lightly tap the proper point on the animal's head where the puncture is to be made through the skull into the brain, which 15 lightly tapping stroke can be made with such small effort on the part of the operator as not to interfere with his aiming his stroke with the greatest degree of accuracy for producing the puncture at the correct or 20 most vital point of the skull of the animal.

While I have illustrated and described what I now regard as the preferred forms of construction for embodying the proposed improvements, I desire to reserve the right 25 to make all such changes or modifications as may fairly fall within the scope of the appended claims.

What I claim is:

1. An animal-knocking tool comprising a 30 cylinder having a handle member projecting at right angles to the axis of said cylinder, a pressure-operated plunger mounted in said cylinder and provided with an axial punch element actuated into outwardly projecting 35 position by the operative movement of said plunger, means movable independently of said punch element and actuated by impact upon the tool, as the same is wielded in the knocking operation, for automatically setting said plunger in operation, and spring means interposed between said plunger and one end of the cylinder and acting yieldingly after each operative movement of said plunger and punch element to retract the 40 same automatically into initial inoperative position.

2. An animal-knocking tool comprising a 45 cylinder having a plunger provided with an axial punch element actuated into outwardly projecting position by the operative movement of the plunger, a combustion chamber in communication with one face of said plunger, means for feeding an explosive charge to said chamber, and ignition means 50 provided with a circuit-closing element actuated by engagement with the animal in the knocking operation.

3. An animal-knocking tool comprising a 55 cylinder having a plunger provided with an axial punch element actuated into outwardly projecting position by the operative movement of the plunger, a combustion chamber in communication with one face of said plunger, means for feeding an explosive 60 charge to said chamber, means for maintain-

ing said plunger normally in retracted position in compressive relation to said charge, and ignition means provided with a circuit-closing element actuated by engagement with the animal in the knocking operation. 70

4. An animal-knocking tool comprising a cylinder having a diaphragm forming a combustion chamber in one end of said cylinder, a plunger operating in said cylinder and provided with an axial punch 75 element actuated into outwardly projecting position by the operative movement of the plunger, said diaphragm having a central port and the corresponding face of said plunger having a boss operating as a valve 80 to close said port in the retracted position of the plunger, means for maintaining said plunger normally in retracted position, means for feeding an explosive charge to said chamber, and ignition means provided with a circuit-closing element actuated by 85 engagement with the animal in the knocking operation.

5. An animal-knocking tool comprising a cylinder having a plunger provided with a 90 punch element actuated into outwardly projecting position by the operative movement of the plunger, a combustion chamber in communication with one face of said plunger, means for feeding a measured quantity 95 of liquid fuel, under pressure, into said chamber, and means set in operation by the wielding of the tool into knocking position for igniting the charge in said chamber.

6. An animal-knocking tool comprising a 100 cylinder having a plunger provided with a punch element actuated into outwardly projecting position by the operative movement of the plunger, a combustion chamber in communication with one face of said plunger, a valve for measuring a quantity of liquid fuel to be fed into said chamber, a compressed-air connection associated with 105 said valve for feeding the charge into said chamber under pressure, and ignition means 110 provided with a circuit-closing element actuated by engagement with the animal in the knocking operation.

7. An animal-knocking tool comprising a cylinder having a plunger provided with a 115 punch element actuated into outwardly projecting position by the operative movement of the plunger, a combustion chamber in communication with one face of said plunger, a hollow handle connected at right angles 120 to said cylinder and maintaining a supply of liquid fuel therefor, means for measuring a charge of liquid fuel to be fed from said handle to said chamber, means for feeding said charge under pressure to said chamber, and ignition means provided with a circuit-closing element actuated by engagement with the animal in the knocking operation. 125

8. An animal-knocking tool comprising a cylinder having a plunger provided with a 130

punch element actuated into outwardly projecting position by the operative movement of the plunger, a combustion chamber in communication with one face of said plunger, a hollow handle connected at right angles to said cylinder and forming a reservoir for liquid fuel, a connection between said reservoir and combustion chamber and provided with a valve for measuring the charge to be fed to said chamber, a compressed-air connection associated with said valve for

mixing air with the fuel and feeding the same into said chamber under pressure, said compressed-air connection also communicating with said reservoir for maintaining the liquid supply therein under pressure, and ignition means provided with a circuit-closing element actuated by engagement with the animal in the knocking operation.

In witness whereof I hereunto affix my signature.

JESSE R. WATKINS.
